UNITED STATES PATENT OFFICE.

FLORENCE L. GRANT, OF FOSTORIA, OHIO, ASSIGNOR TO GENERAL ELECTRIC COMPANY,
OF NEW YORK, N. Y., A CORPORATION OF NEW YORK.

DESIGN FOR A LAMP SHADE OR REFLECTOR.

43,418.

Specification for Design.

Patented Jan. 7, 1913.

Application filed October 12, 1912. Serial No. 725,524. Term of patent 14 years.

To all whom it may concern:

Be it known that I, FLORENCE L. GRANT, a citizen of the United States, residing at Fostoria, county of Seneca and State of Ohio, have invented a new, original, and ornamental Design for Lamp Shades or Reflectors, of which the following is a specification, reference being had to the accompanying drawing, forming part thereof.

The figure is an elevation of a reflector showing my new design.

I claim—

The ornamental design for a lamp shade or reflector as shown.

FLORENCE L. GRANT.
